CENTRIFUGAL MOLDING OF CONCRETE PRODUCTS

Russell Juan van Niekerk, Florida, Transvaal,
Union of South AfricaApplication August 20, 1942, Serial No. 455,513
In the Union of South Africa October 7, 1941

4 Claims. (Cl. 25—155)

This invention relates to the centrifugal molding of concrete products, particularly concrete poles and pipes, and the lining of pipes with concrete, bitumen or like material.

Hitherto, in the centrifugal molding of concrete products and lining of pipes, the initial distribution of the concrete in the mold or the lining material in the pipe has been a process occupying considerable time or involving a considerable expense of labor. The customary method of distribution has been to introduce the concrete or lining material in successive charges and to rotate the mold or pipe slowly, with or without vibration, until the charge has become distributed along the length of the mold or pipe. It has also been proposed to mount the mold or pipe for charging purposes in a stationary position on a beam or frame which can be tilted so as to bring the mold or pipe to an inclined position with its charging end upwards, whereafter the concrete or lining material is delivered into the open end and descends down the mold or pipe by gravity. This method, however, involves the subsequent process of bringing the beam or frame to the horizontal, then removing the mold or pipe therefrom and placing it in a separate machine for spinning the mold or pipe, the machine being first rotated at a relatively slow speed so as to complete the distribution of the concrete or lining material.

One of the objects of the present invention is to facilitate and expedite the distribution of the concrete or lining material in the mold or pipe.

A further object is to facilitate the spinning of the mold or pipe in a manner best calculated to ensure the consolidation of the concrete or lining material in a uniform manner throughout the product or lining to be formed.

A still further object is to enable hollow poles, pipes or like products to be spun with a wall of substantially the same thickness throughout the length thereof, or with a wall varying in thickness in a predetermined manner and degree. In particular, it is an object of the invention to enable tapered hollow poles, pipes and like tapered products to be spun with a wall of uniform thickness throughout, i. e., with a tapered external surface and an internal surface tapered similarly, thus avoiding wastage of material and effecting a saving in weight of the product, as compared with tapered hollow products manufactured hitherto, in which the bore or internal surface is cylindrical or parallel, or at any rate not tapered in agreement with the external taper of the wall, and the thickness of the wall at the

wider end of the product consequently in excess of what is required for purposes of strength.

Another object of the invention is to provide a simple and inexpensive machine for distributing and spinning the concrete or lining material.

According to this invention, I provide a method of centrifugally molding concrete products or centrifugally lining pipes in which the mold or pipe, during the charging of the concrete or lining material, is rotatably supported in an inclined position and is rotated in this position so as to distribute the concrete or lining material along and within the pipe by a combined gravity and rotational action.

15 In accordance with a further feature of the invention, the method is such that the mold or pipe, when the concrete or material has been properly distributed therein, is spun at any desired speed, while lying at any desired inclination, so as to consolidate the concrete or lining material by centrifugal force, while still keeping non-consolidated concrete or lining material under the combined control of the centrifugal force and gravity.

20 According to another feature of the invention, a machine for centrifugally molding concrete products and lining pipes comprises means whereby the mold or pipe is rotatably supported and whereby it is, while so supported, variable in

25 inclination, and means for rotating or spinning the mold or pipe at any given inclination at different speeds.

30 The invention will now be described, by way of example, with reference to the annexed drawing, in which—

35 Fig. 1 is a view in side elevation of a machine embodying the invention and showing a mold therein;

40 Fig. 2 is a plan view of the machine shown in Fig. 1 without the mold;

45 Fig. 3 is a relatively enlarged view of part of the machine shown in Figs. 1 and 2.

Referring to the drawing:

The machine comprises a beam 1 (e. g. consisting of a pair of plate girders suitably braced) which is pivotally mounted on a trunnion bearing or fulcrum 2, which in the case illustrated is offset a distance from the middle of the beam towards the right-hand end. The fulcrum 2 is supported in a bearing block or blocks 3 which is or are mounted on a foundation or floor 4 in which a well 5 is formed in order to permit the beam 1 to be tilted to any angle within a given range. The beam 1 is provided towards the end 55 thereof remote from the fulcrum 2 with a trans-

verse bar 6, over the ends of which are adapted to be fitted rings 7 provided on the ends of chains 8 which are connected to an electric crane, hydraulic jack or other suitable means (not shown) for the purpose of raising and lowering the beam 1 to the particular inclination desired, e. g., the position shown in dotted lines in Fig. 1.

At intervals along the beam 1, pairs of supporting rollers 9, 10 are mounted on bearing brackets 11. The drive of an electric motor 12 mounted on the beam 1 is transmitted by means of belt or other gearing 13 to one of the pairs of supporting rollers, viz. the pair of rollers 9, 10 above the fulcrum 2.

In Fig. 1, a tapered mold 14 made in two halves is shown mounted in the machine. This particular mold is one adapted for the centrifugal molding of a tapered reinforced concrete pole. It is fitted with a reinforcement positioning device comprising a clamp or holder 15 at one end of the mold, and a positioning plate or element 16, a second clamp or holder 17, and a screw-tensioning means 18 at the other end of the mold, all as specified in my co-pending application No. 455,514.

On the mold 14, spinning rings 19 are provided at the same intervals apart as the pairs of supporting rollers 9, 10. These rings are fixed rigidly and coaxially upon the mold 14 and rest, and are adapted to roll, upon the rollers 9, 10. Thus, on the electric motor 12 being set in operation, the rollers 9, 10 driven by the belt or other gearing 13 cause rotation of the mold 14 about its axis, the speed of this rotation being varied by variation of the speed of the motor.

As indicated in Fig. 3, a displaceable jockey-roller 20 carried by a bent-arm lever 21 is associated with each pair of supporting rollers 9, 10. This jockey-roller 20 is adapted to be brought into rolling contact with the top of the corresponding spinning ring 19 and to be held in such contact with a greater or smaller degree of pressure by an adjustment nut or handle 22 which is turnable on the screw-threaded end 23 of a retaining lever 24. In this manner, the mold 14 is retained on the rollers 9, 10 during spinning, and chattering or undue vibration of the mold is avoided.

In order to prevent lengthwise movement of the mold 14, the end spinning rings 19 are formed with double flanges 25, 26 and the intermediate spinning rings 19 are formed with single flanges 27, the side surfaces of the flanges 25, 26 and 27 being adapted to take up end-thrust by contact with the corresponding side surfaces of the respective supporting rollers 9, 10.

The end of the beam 1 remote from the fulcrum 2 may be termed the charging end of the machine, and is fitted with a charging hopper 28, the mouth or forward part 28a of which is tapered and adapted to project a short distance into the adjacent end of the mold 14. The mold 14 (or the pipe, as the case may be) is placed in the machine so that its larger end is the end into which the concrete (or lining material) is charged. This end is the end which is elevated when the beam 1 is tilted. For the purpose of charging the concrete into the mold from the hopper 28, the reinforcement clamp or holder 15 is made of annular shape so as to provide the necessary opening through which the concrete may enter the mold.

The method of molding (or lining) with the machine described is as follows:

The beam 1 is set in a horizontal position in

order to receive the mold 14, this latter, in the particular case described, having previously had the reinforcing wires (parts of which are indicated diagrammatically by dotted lines 29 in Fig. 1) positioned therein by the positioning devices 15 to 18 already referred to.

The mold 14 is placed so that the spinning rings 19 rest upon the supporting rollers 9, 10 and is retained in this position by bringing over on top of the spinning rings 19 the jockey-rollers 20, and securing them in place by the handles 22 and screw-threaded levers 24.

The hopper 28 is charged with the quantity of concrete required, and the electric crane or other hoisting means (not shown) connected by the chains 8 and rings 7 to the transverse bar 6 is operated so as to tilt the beam 1 and mold 14 thereon to a fairly substantial inclination, such as the position shown in Fig. 1 in dotted lines. In this position, the electric motor 12 is switched on so as to set the mold 14 rotating slowly, and the concrete in the hopper 28 is charged into the large end of the mold. By virtue of the rotation, and inclination of the mold, the concrete is distributed around its interior.

When this preliminary distribution is complete, the beam 1 is lowered from the dotted position (Fig. 1) to the level or to an inclination suitable for high-speed spinning, i. e. for consolidating the pole or other product by centrifuging. In the case of a cylindrical or parallel-sided product, this level will be the horizontal position as shown in full lines in Fig. 1. In the case of a tapered product (such as the tapered reinforced-concrete pole particularly described above), the inclination will be at an angle approximating to the horizontal, but considerably less than the angle of the beam shown in dotted lines in Fig. 1. More specifically, the inclination is necessarily such that the effect, during centrifuging, of the taper of the mold (viz. to cause creeping of the centrifuged concrete from the smaller to the larger end of the mold) will be counteracted by the gravitational effect on the concrete produced by the inclination of the mold. These two opposing effects being balanced, the concrete during centrifuging will be subjected purely to a centrifugal or radical consolidation, and the original uniformity of distribution of the concrete in the mold will not be disturbed, and a product with a uniformly thick wall, with its internal and external surfaces tapered alike, will be obtainable.

Thus during centrifuging, the whole of the concrete, including concrete not yet consolidated, is under the combined control of centrifugal force and gravity, in such a manner as to make possible whatever distribution and consolidation of concrete is desired.

When molding or consolidation of the product is complete, rotation of the mold 14 is stopped by switching off the motor 12. Thereafter, the mold and beam 1 are lowered to the horizontal position, the handles 22 are unscrewed, the levers 21 carrying the jockey-rollers 20 swung back, and the mold removed from the machine, for eventual withdrawal therefrom of the molded product.

As will be appreciated, the inclination of the mold, and its speed of rotation, may both be varied at will in the course of the distributing and/or centrifuging operations, without the necessity of stopping, or in any way interfering with, the work. The mold (or the pipe in the case of a pipe being centrifugally lined) is always under

complete control, so that any tendency towards lengthwise creeping of the concrete (or lining material), or incorrect rate or degree of consolidation at one end or another of the mold (or pipe), can immediately be rectified.

While the method of operation has been particularly described with reference to the molding of a tapered reinforced-concrete pole, it will be obvious from the indications already given that the machine may also be used for molding parallel or cylindrical poles and tapered or parallel hollow bodies or pipes, and for the centrifugal lining of hollow bodies or pipes.

Various modifications may be made in the machine described, without departing from the scope of the invention. For example, instead of retaining the spun body on the supporting rollers 9, 10 by means of jockey-rollers 20, I may employ for this purpose endless belts or equivalent means.

In the appended claims, the term "centrifuging" is intended to include centrifugally molding concrete products and centrifugally lining pipes, the term "hollow body" is intended to include a mold to be charged with concrete and a pipe to be charged with lining material, and the term "material" is intended to include the concrete or lining material.

I claim:

1. A method of molding a hollow tapering concrete product, consisting in inclining and slowly rotating an appropriate mold with its larger end uppermost while charging the same with material, and then subjecting the mold and material to a rapid rotation while maintaining the inclination of the mold at a degree to cause an incident gravitational influence on the material sufficient to overcome the tendency of the material to creep toward the larger end of the mold under the centrifugal operation.

2. A method of molding a tapering concrete product to produce an article having substan-

tially even wall thickness throughout, consisting in slowly rotating a tapered mold while steeply inclined downwardly from its larger end, feeding the material into the larger end and distributing such material throughout the mold through such rotation and initial inclination, then materially increasing the rotation while varying the inclination to a degree to develop a gravitational influence on the material to overcome the tendency of the material to creep under the centrifugal influence, whereby to insure a wall of substantially uniform thickness throughout.

3. A method of molding hollow concrete products of tapered form with substantially uniform wall thickness throughout, consisting in mounting an appropriate mold for pivotal and rotative movement, inclining the mold with the larger end uppermost and slowly rotating to insure gravitational feed and rotative spread of the material, feeding the material onto the mold, and then rotating the mold to develop centrifugal action for increasing the rapidity of setting of the material while at the same time arranging the inclination of the mold at a degree to influence the material by gravity to overcome the tendency of the material to creep toward the larger end of the mold incident to the centrifugal influence.

4. A method of molding hollow tapered concrete products with substantially uniform wall thickness, consisting in inclining the mold for gravitational feed of the material lengthwise with the same, placing the material in the mold, and rotating the mold at a relatively slow speed for distributing the material, and then rotating the mold at a relatively high speed for centrifugal placement and to increase the rapidity of setting of the material while maintaining the mold at a predetermined inclination to develop a gravitational influence to counteract creeping influence of the material under centrifugal action.

RUSSELL JUAN VAN NIEKERK.
